GASIFICATION OF CARBONACEOUS SOLIDS

Everett Gorin, Whitehall, Pa., assignor to Pittsburgh Consolidation Coal Company, Pittsburgh, Pa., a corporation of Pennsylvania

Application February 4, 1950, Serial No. 142,466

2 Claims. (Cl. 48—206)

1

This invention relates to the gasification of carbonaceous solid fuels, and, more particularly, to the manufacture of carbon monoxide and hydrogen by the reaction of steam and carbon in fluidized systems.

It is generally most economical to use as the solid feed material to a steam-carbon fluidized gasification vessel a carbonaceous material produced by once-through grinding without any intermediate classification of the solids. The resulting grind has a rather wide particle size distribution which requires that a relatively high linear velocity be employed to provide good fluidization. Under these high velocity conditions, the solid fines are selectively elutriated from the vessel.

It has been found that the fines cannot be efficiently gasified even when they are returned to the fluidized bed by means of a cyclone. The reason for this is that the fines circulate so rapidly between the bed and the cyclone that their residence time in the bed is very short. As a matter of fact, a considerable portion of the fines must be removed from the cyclone before returning to the system to prevent the fines re-circulation rate from building up to an unmanageable figure. This phenomenon causes the loss of carbon through incomplete gasification of the fines.

Another disadvantage of the conventional type of fluidized system is the difficulty in obtaining a high steam conversion at the high linear velocities required to obtain good fluidity with beds of manageable height. This is true particularly when operating under pressure since, under these conditions, the mass velocity of steam put through the bed increases more rapidly than the rate of carbon-steam reaction.

The present invention provides for the introduction of carbonaceous solids ground to a wide range of particle sizes into a fluidized bed and for the circulation of steam through the bed under reaction conditions. The necessary heat is preferably supplied by the introduction of oxygen into the system to effect partial combustion of the solids. The velocity of the fluidizing gases is such as to maintain a condition of good fluidity in the bed with consequent elutriation of a substantial proportion of solid fines. These fines I have found have a higher average carbon content than that of the bed proper because of their short residence time in the bed. The effluent gases (including unreacted steam) and elutriated solid fines from this fluidized bed of carbonaceous material are con-

ducted into an upper fluidized bed of such geometric configuration that the upflow velocity in the second bed is less, preferably by a factor of three to ten, than that prevailing in the lower bed. As a consequence, the elutriated fines are retained in this bed and because of their relatively narrow size range, lose little by elutriation at the lower velocity. The temperature of the upper bed is maintained at suitable reaction temperature to complete the gasification of solid carbonaceous fines.

This procedure has the following advantages:

1. Due to the narrower and finer average size consist of the particles entrained from the lower bed, good fluidity is achieved in the upper bed at the lower velocity with the very substantial decrease in entrainment rate from the upper bed.

2. Due to the relatively low velocities prevailing in the upper bed, high over-all steam conversions are obtained and

3. Higher over-all carbon efficiency is obtained.

Other objects and advantages of my invention will become apparent upon reference to the following detailed description and the accompanying drawing in which is shown a diagrammatic illustration of a preferred embodiment of my invention.

Referring to the drawing, a description of the apparatus and its operation for gasifying coal will now be described. It is understood, however, that any carbonaceous solid fuel capable of reacting with steam to produce carbon monoxide and hydrogen may be used.

Coal from a hopper 10 is fed to a crusher 12 where the coal is ground to a range of particle sizes, preferably from about 325 to about 14 mesh. The finely divided crushed coal is then fed through conduit 14 into another conduit 16 where it is picked up by steam and conveyed to a fluidizing vessel 18. Additional steam is introduced into the vessel 18 through conduit 20 and is distributed by a porous plate 21 into the fluidized bed. The oxygen required for heat is introduced through conduits 22 and 24 into conduit 20. The superficial linear velocity of the gases circulating through the vessel 18 is regulated so as to establish and maintain a bed of the finely divided coal in a fluidized condition. This linear velocity preferably lies between 0.75 and 3.0 feet per second. The amount of oxygen fed to the vessel is sufficient to elevate the temperature of the bed and maintain it at steam-carbon reaction temperatures, preferably in the neighborhood of

3

1800° F. The solid residue or ash from the steam carbon reaction is withdrawn through discharge conduit 26 as required to maintain the level of the fluidized bed.

The effluent gases, including unreacted steam, from the fluidized bed in vessel 18 and the elutriated fines are conveyed through conduit 28 which in turn communicates with a manifold conduit 30. The latter is provided with a plurality of feed conduits 32, in which the gases and fines are conducted to a second vessel 34. This vessel is provided with a plurality of cones along its bottom to which the feed conduits 32 are connected. Each of the cone shaped members has grid member 36 disposed therein above the apex of the cone but below the point of introduction of the effluent gases and fines from vessel 18. Oxygen is introduced into the vessel 34 through a plurality of conduits 38 leading from the oxygen conduit 22. The feed conduits 32 open into the vessel 34 at a point sufficiently above the grids to insure that all of the oxygen is consumed by reaction with the carbon before it has a chance to mix with the products of vessel 18. Additional steam may be introduced along with the oxygen from a conduit 39 communicating with conduit 22. This may be desirable in those cases where the volume of oxygen is insufficient to fluidize the bed in vessel 34.

The linear velocity of the gases circulating through vessel 34 is reduced below that maintained in vessel 18 so that the solid fines are carried by the effluent gases are retained in vessel 34 in a fluidized condition. This reduced velocity preferably is between 0.05 and 0.5 feet per second. The temperature within the vessel 34 is maintained at substantially the same level as that in 18 by means of the oxygen introduced. In view of the lower linear velocity of the fluidizing gases, only a small percentage of fines is elutriated by the effluent gases from the fluidized bed in vessel 34. These may be returned to the bed by means of one or more cyclones, 40. The solid free product is then recovered through conduits 42 which communicate with a common exit line 43. The solid residue or ash is withdrawn through a plurality of discharge conduits 44 communicating with each of the cone shaped members along the bottom of the vessel 34.

In the operation of a system of the above type, it is necessary to maintain a balance between the inventories and linear velocities in the two vessels such that (1) good fluidity is obtained in both vessels; (2) the elutriation rate from the lower vessel is not substantially greater or smaller than that required to supply the carbon requirements to convert the steam passed through the upper bed; and (3) the elutriation rate from the upper vessel is maintained small. The required interrelationship between the several variables may be made less critical by providing for recycle of fines between the upper and lower beds by means of a standpipe 46 disposed to automatically return the surplus fines from the upper to the lower beds.

The exact relationship between liner velocity, size consist and bed inventories will depend on the nature of the solid fuel, its size distribution and the bed temperatures and pressures. It is usually convenient to operate the system in such a manner that from 30-60% of the carbon fed to the system is gasified in each of the vessels. This means that approximately one-half of the ash is removed from each vessel. In order to accomplish the same amount of gasification in both

4

the upper and lower beds, the carbon inventory in the upper bed must be at least twice that in the lower bed. This is required to compensate for the retardation of the gasification rate by the gasification products.

The outlet velocity from the lower bed may be based on the median particle diameter. The median particle diameter is defined as the diameter of the sieve opening which holds up fifty weight percent of the charge. The outlet velocity from the lower bed is, therefore, generally regulated to lie within the velocity range from 25-150% greater than the terminal velocity for free fall of a particle having this median diameter. The terminal velocity is a function of the particle size, shape, density and gas viscosity and may be readily calculated from established equations. Similarly, the outlet velocity from the upper bed is regulated to lie within the range of 10-75% greater than terminal velocity for free fall of a particle having the median diameter of the upper bed.

The preferred linear velocity employed depends to some extent on the nature of the particle size distribution as well as on the median particle diameter. The size distribution of most grinds obeys the Rosin Rammler equation fairly well.

$$R/100 = 10^{-bx^n}$$

where R is the cumulative weight percent of particles having a diameter greater than x ; and b and n are constants characteristic of the particular grind employed.

A number of commercial grinds of a typical char produced by the low temperature distillation of coal with the corresponding values of b , n , median particle diameter and suitable range of outlet linear velocities to employ in the lower gasification bed of a two vessel system are given in the table below.

Table I

Sieve Opening	R					
	Mesh	X=microns	Grind #1	Grind #2	Grind #3	Grind #4
+28		589	9.2	4.3	3.2	0
+35		417	17.0	9.7	9.4	3.4
+65		208	48.4	30.1	24.4	11.2
+100		147	60.6	45.1	51.0	39.2
+200		74	80.0	67.3	71.6	64.8
+325		44	87.5	80.7	83.5	78.0
-325			100.0	100.0	100.0	100.0
b		.000568	.00195	.000894	.00186	
n		1.18	1.04	1.18	1.10	
Median Particle Diameter, Microns		200	130	144	104	
Terminal Velocity of Median Particle, ft./sec.		1.9	0.6	0.75	0.4	
Linear Velocity Range in Lower Bed		2.3-4.0	1.0-1.5	1.0-1.9	0.5-1.0	

The above figures apply to the gasification of low temperature char with oxygen-steam mixtures at atmospheric pressure and 1800° F. It is to be understood that velocity figures cited will vary with the operating conditions i. e. the velocities increase as the density of the fuel increases and decrease as the pressure increases.

The linear velocity to be employed in the lower bed is a function of the value of n as well as the median particle diameter. The velocity employed should fall in the upper part of the range specified above when n is low i. e. less than 1.1 and in the lower part of the range when n is high i. e. greater than 1.1.

The fineness of the grind that it is best to

employ depends on the operating pressure and temperatures. Fine grinds having median particle diameters less than 125 microns are preferably employed when operating at pressures in excess of 100 p. s. i. or at temperatures below 1750° F. On the other hand, when one operates at pressures below 100 p. s. i. or at temperatures above 1750° F., it is best to employ grinds having median particle diameters in excess of 125 microns in order to obtain full advantage of high capacities as allowed by the kinetics of the gasification reaction. It should be pointed out that in those cases where the size range of the solids fed to the first reaction zone is a very wide one, it may be desirable to employ more than one additional reaction zone, with each successive zone containing progressively narrower size ranges of progressively smaller particles, with correspondingly lower velocities of the fluidizing gases.

The operation of the two bed system is summarized in a typical case of a feed comprising a low temperature char in the table below.

Table II

Bed	Feed	Linear Vel., F. P. S.		Bed Depth, ft.	Bed Temp., ° F.	Steam Conv., Percent of Initial Chg.
		Initial	Final			
Lower-----	Char-Oxygen-----	1.1	1.5	8.0	1,800	40

Upper Bed-----				1.2	11.2	16.7
					32.1	3.4
						23.7

The entrainment rate was of the order of 0.01 lb./s. c. f. from the upper bed as compared with an entrainment rate of 0.07 lb./s. c. f. from the lower bed.

According to the provisions of the patent statutes, I have explained the principle, preferred construction, and mode of operation of my invention and have illustrated and described what I now consider to represent its best embodiment. However, I desire to have it understood that, within the scope of the appended claims, the invention may be practiced otherwise than as specifically illustrated and described.

I claim:

1. The method of gasifying a carbonaceous solid fuel which comprises feeding said solid fuel in a finely divided state that includes a range of particle sizes to a gasification reaction zone, passing steam in contact with said solids fuel in said reaction zone under steam-carbon reacting conditions and at a linear velocity sufficiently high to establish and maintain a turbulent dense solids phase superimposed by a dilute solids phase, discharging ash from said reaction zone as required to maintain the level of said dense solids phase, withdrawing the effluent gases including unreacted steam together with entrained solid fines from said dilute solids phase 70 and conducting same to a second and separate gasification reaction zone, passing said effluent

gases including said unreacted steam in contact with said solid fines in said second reaction zone under steam-carbon reacting conditions and at a linear velocity which is less than that of the gas passing through said first reaction zone but which is sufficiently high to establish and maintain a turbulent dense solids phase superimposed by a dilute solids phase, maintaining the carbon inventory in said second reaction zone at least twice that in the first reaction zone, and recovering the gaseous products from said second reaction zone.

2. The method of gasifying a carbonaceous solid fuel which comprises feeding said solid fuel in a finely divided state that includes a range of particle sizes to a gasification reaction zone, passing steam in contact with said solids fuel in said reaction zone under steam-carbon reacting conditions and at a linear velocity sufficiently high to establish and maintain a turbulent dense solids phase superimposed by a dilute solids phase, discharging ash from said reaction zone as required to maintain the level of said dense solids

phase, withdrawing the effluent gases including unreacted steam together with entrained solid fines from said dilute solids phase and conducting same to a second and separate gasification reaction zone, passing said effluent gases including said unreacted steam in contact with said solid fines in said second reaction zone under steam-carbon reacting conditions and at a linear velocity which is less than that of the gas passing through said first reaction zone but which is sufficiently high to establish and maintain a turbulent dense solids phase superimposed by a dilute solids phase, maintaining the carbon inventory in said second reaction zone at least twice that in the first reaction zone, returning the fines in excess of a predetermined level in said second reaction zone to the dense phase in said first reaction zone, and recovering the gaseous products from said second reaction zone.
